UNITED STATES PATENT OFFICE.

AUGUST F. KIRSCHBAUM, OF ST. PAUL, MINNESOTA.

LUBRICATING DEVICE.

1,072,619.

Specification of Letters Patent.

Patented Sept. 9, 1913.

Application filed February 13, 1912. Serial No. 677,299.

To all whom it may concern:

Be it known that I, AUGUST F. KIRSCHBAUM, a citizen of the United States, residing at St. Paul, in the county of Ramsey 5 and State of Minnesota, have invented certain new and useful Improvements in Lubricating Devices, of which the following is a specification.

My invention relates to improvements in 10 lubricating devices, its object being particularly to provide an improved device for oiling the guideways for elevators and for equivalent uses, and to this end consists in the features of construction, combination, 15 and arrangement of parts hereinafter described and claimed.

In the accompanying drawings forming 20 part of this specification, Figure 1 is a top view of my improved device shown in connection with an elevator guideway; Fig. 2 is a side elevation of the same partly broken away; Fig. 3 is a front elevation shown sectioned on line $x-x$ of Fig. 1; and Fig. 4 is a detail view of an actuating lever forming 25 part of the invention.

Referring to the drawings A represents 30 a receptacle for the oil provided with a suitable cover 2, the receptacle being supported upon the elevator B as by means of brackets 3. The elevator forming no part of my invention is only shown fragmentarily. Leading from the bottom of the receptacle is a downwardly extending conduit plug 4 tapped into which is a laterally and downwardly 35 extending tube 5 constituting a discharge conduit for the oil. Slidable in the tube 5 is a plunger 6, normally held outward by a coil spring 7 arranged within the tube and interposed between the plunger 40 and conduit closing plug 8. The plunger 6 is loose within the pipe 5 to allow oil to pass over it, the free end of the plunger wiping the guideway 9 to deposit the oil thereon. The inner end of the discharge 45 conduit is closed by a valve formed by the lower end of the rod 10, said rod at its upper end having pivotal connection 11 with the outer end of a link 12 supported on a transverse rod 13 journaled in the sides of 50 the receptacle. The rod 13 is normally held in position closing the valve by means of a spring 14 connecting one end of the rod with the receptacle. Secured upon the opposite end of the rod is an arm 15, said 55 arm at its free end pivotally supporting an extension arm 16 through the medium of a

pivot 17. The extension arm 16 is normally held in alinement with the supporting arm 15 by means of a lateral finger 18 carried by the inner end of the extension arm, the finger 18 being normally held in contact with the underside of the arm 15 by the overweighted outer end of the extension arm. The outer end of the extension arm is thus free to swing upwardly but is held 60 against swinging downwardly. A stop 19 is positioned at a suitable point along the guideway to engage with the extension arm, as indicated in Fig. 1.

In use, the elevator as it travels upwardly 70 upon the guideway, carrying with it the lubricant reservoir, will cause the free end of the extension arm 16 to be brought into contact with the stop 19. As the elevator continues to travel upward the engagement 75 of the stop 19 with the arm 16 will, through the intermediate mechanism, lift the valve 10 and allow a certain quantity of oil to pass downwardly through the discharge tube around the plunger 6, the oil being wiped 80 upon the guideway by the plunger. As the extension arm 16 is carried past the stop 19 the parts will be restored to normal position by the spring 14. In the downward travel of the elevator, the engagement of the 85 stop 19 with the extension arm 16 turns said arm upon its pivot without affecting the normal position of the parts. Any desired number of the stops 19 may be used to regulate the amount of oil discharge from the 90 reservoir.

While I have shown my invention applied to an elevator for oiling the guideway, I may employ the same for any equivalent oiling.

I claim as my invention:

1. Lubricating means of the class described comprising a reservoir formed with a discharge opening, a valve within said reservoir normally closing said opening, a lever arm pivotally supported in said reservoir and at its inner end pivotally supporting said valve, an extension arm fulcrumed upon said first mentioned arm, means for holding said extension arm against turning in one direction while allowing it to turn upon its fulcrum in the opposite direction, and means for engaging said extension arm and turning it with said first mentioned arm to open said valve for the purpose set 105 forth.

2. In combination with a traveling ele-

ment, an oil reservoir supported thereby, said reservoir being formed with a laterally extending discharge conduit, a spring pressed oil delivery piston slidably and loosely supported in said conduit, a valve normally closing the inner end of said conduit, a fulcrumed arm supported by said reservoir and at its inner end pivotally supporting said valve, an extension arm fulcrumed upon said first mentioned arm, means holding said extension arm against being

turned upon its fulcrum in one direction but allowing it to be turned in the opposite direction, and a stop arranged in the path of said extension arm for the purpose set forth. 15

In testimony whereof I affix my signature in presence of two witnesses.

AUGUST F. KIRSCHBAUM.

Witnesses:
